UNITED STATES PATENT OFFICE.

DAVID A. SEALEY, OF NEW YORK, N. Y.

BALANCED DIAPHRAGM FOR SOUND TRANSMITTERS.

Application filed July 8, 1922. Serial No. 573,613.

To all whom it may concern:

Be it known that I, DAVID A. SEALEY, a citizen of the United States, residing at New York city, in the county of New York and State of New York, have invented certain new and useful Improvements in Balanced Diaphragms for Sound Transmitters, of which the following is a specification, reference being had to the accompanying drawings.

This invention relates to sound transmitting apparatus, such as phonographs, telephone receivers, etc., and particularly to the diaphragm mountings therefor.

In the ordinary sound transmitting apparatus which uses a diaphragm, the diaphragm is clamped at its extreme margin between gaskets or other clamping devices and there is no balance to the pull or thrust exerted at the center of the diaphragm.

The general object of my invention is to provide a diaphragm for transmitting or receiving apparatus wherein the diaphragm is not supported or clamped at its extreme margin but inward of the perimeter of the diaphragm, means being provided engaging the perimeter or engaging the diaphragm beyond the annular fulcrum or clamping means which will balance the resistance or stiffness of the diaphragm or balance the pull or force exerted at the center of the diaphragm.

My invention is illustrated in the accompanying drawing, wherein:—

Figure 1 is a section of a phonographic sound box having a diaphragm constructed in accordance with my invention;

Figure 2 is a section of a telephone transmitter showing my improved diaphragm;

Figure 3 is a section of a wireless receiver showing my improved diaphragm;

Figure 4 is a fragmentary section of a telephone transmitter with springs instead of having a weighted perimeter;

Figure 5 is a face view of a diaphragm with a continuous weight around its perimeter;

Figure 6 is a front view of a diaphragm with weights disposed at intervals around its perimeter.

In Figure 1, I have illustrated the application of my invention to a phonograph diaphragm, and in this Figure 10 designates

the ordinary sound box of a phonograph, which may be of any suitable construction, the construction not having anything to do with my invention, and 11 designates the diaphragm, which may be of mica, glass, steel, or any other suitable material and which may be in all respects precisely the same as an ordinary diaphragm. This diaphragm is supported inward of its perimeter by means of annular gaskets 12 shown as engaged with seats 13.

I have illustrated the sound box 10 as being formed in two parts held in close engagement with each other by screws 14 whereby the gaskets may be clamped against the diaphragm, but it will be understood that this figure is purely diagrammatic and that the manner of construction of the sound box and the manner in which the gaskets are supported therein may be varied in many ways. The diaphragm 11 at its perimeter is shown as weighted by a weight 75 or weights 15. I have illustrated a circular rod of lead or other suitable metal which has been cleft radially and forced upon the perimeter of the diaphragm and extends entirely therearound, but I do not wish to be limited to this, as any other suitable material may be used for this purpose and the weight need not extend entirely around the diaphragm. A number of weights may be used placed at spaced intervals, as illustrated in Figure 6. Furthermore, this weight need not be of metal but might be made of a rubber strip attached to the perimeter of the disk. In all cases, however, the member 15 which is attached to the 90 perimeter of the diaphragm acts as a counterbalance to the thrust or force exerted at the center of the disk and preferably this weight will extend equally on both faces of the diaphragm. The stylus arm 16 may be, 95 of course, of any suitable character and has no bearing on my invention.

In Figure 2, I have illustrated the sound box of a telephone receiver or transmitter which, of course, includes the diaphragm 11. This diaphragm is illustrated as being supported between gaskets 12 disposed inward of the perimeter of the diaphragm and the diaphragm is illustrated as being weighted at its extremity, as at 15. This weight, as before remarked, may extend en-

tirely around the perimeter of the dia-phragm or there may be a series of weights disposed at intervals around the perimeter of the diaphragm.

5 Figure 2 is purely diagrammatic and is merely to illustrate the fact that the dia-phragm counter-balanced as described may be used in a telephone receiver or transmitter or any other apparatus where the dia-phragm is magnetically affected by the core 17 of an electro-magnet.

In Figure 3, I have illustrated the receiver of a wireless telephone and the figure is typical of many other electro-magneti-cally operated receivers. In this case the sound box or casing of the receiver 18 carries within it an electro-magnet 19 acting on an armature 20, this armature being connected by a rod 21 to a disk or diaphragm 20 11^b. This diaphragm may be of mica, glass or any other suitable material. Here again the diaphragm is supported inward of its perimeter by the opposed clamping gaskets 12^b and the perimeter of the dia-phragm is weighted, as at 15^b. This weight may extend entirely around the diaphragm or be disposed at intervals. Here again the figure is purely diagrammatic and is merely for the purpose of illustrating the fact that 30 a weighted diaphragm may be used with a receiver of this type. In Figure 4, I have illustrated a diaphragm 11^c which is sup-ported by the gaskets 12^c, but the perimeter of the diaphragm is counter-balanced not by a weight but by opposed springs 22.

It will be seen that in all cases I balance the pull or thrust exerted on the center of the diaphragm either by a stylus arm 16, by the electro-magnetic traction, as in Figure 2, or by the pull of the rod 21, as illus-trated in Figure 3, to thereby render the disk more flexible. I have found by exper-iment that a relatively heavy or stiff disk can be rendered quite flexible by the counter-balancing weights or springs. A counter-balanced disk permits a much easier move-ment of the diaphragm and causes the dia-phragm to respond much more readily to the movement of the needle on the record or 50 to the fluctuation in the magnetic field than where the disk is not counter-balanced. My experiments have shown me that a dia-phragm arranged as described produces louder tone and a tone of much better qual-ity. I have found in actual experience that 55 a metal diaphragm as used, for instance, in the ordinary telephone transmitter or re-ciever is rendered very pliable and the slightest variations of the induced current 60 in the magnet produces a corresponding movement in the diaphragm if the dia-phragm is weighted or otherwise counter-balanced as described.

While I do not wish to be limited to this, 65 this invention is particularly applicable to

the receivers and transmitters used with wireless telephones. Neither do I wish to be limited to the exact balancing of the dia-phragm by the application to its perimeter of weights or springs which will exactly 70 counter-balance the force exerted at the center of the diaphragm, and it is within the purview of my invention for the weight on the perimeter of the diaphragm to be a lit-tle less or a little greater than is required to 75 exactly balance the force at the center of the disk. I have found that in actual prac-tice the diaphragm is rendered very flexible and vibrates much more easily and with much greater rapidity than where no 80 weights are used upon the perimeter of the diaphragm but the diaphragm is clamped around its perimeter. The theory with re-gard to this action is as follows:—

It will be seen that the diaphragm is 85 pivoted or fulcrumed on a circle 12. There is a certain pull or thrust at the center of the diaphragm and if a portion of the dia-phragm is considered as a lever pivoted at 13 and having a weight at its outer end and on the short arm of the lever and connected at its inner end to a thrust-exerting member such as the stylus bar 16, then if the weight at the perimeter or end exactly balances this pull or thrust 90 the center of gravity of the lever is at the fulcrum point and is exactly balanced about its point of support and this lever or section of the diaphragm oscillates at the end cor-responding to the center of the diaphragm 100 and at its perimeter or weighted end. If now the weight on the perimeter is a little less or a little greater than required to ex-actly balance the force at the center of the disk, there is a condition which is analogous 105 to that of a pendulum swinging on its ful-crumb. It has been desired to clamp the dia-phragm inward of its perimeter so as to per-mit the better flexing of the diaphragm, but I have found that this is not practical unless 110 the weights or the springs 22 are used to more or less balance that portion of the dia-phragm between the annular fulcrum and the center of the diaphragm where the thrust or force is exerted.

115 I claim:—

1. In a sound transmitting apparatus, a dia-phragm, clamping means for the dia-phragm rigidly engaging the opposite faces of the dia-phragm inward of its periphery and disposed concentric to the center of the dia-phragm whereby the perimeter of the dia-phragm may flex, means located adja-120 cent the center of the dia-phragm whereby force may be applied thereto to vibrate it, and means engaging the dia-phragm adja-125 cent its perimeter for approximately coun-ter-balancing said force.

2. In a sound transmitting apparatus, a dia-phragm, clamping means for the dia-130

phragm rigidly engaging the opposite face thereto to vibrate it, the perimeter of the of the diaphragm inward of its periphery diaphragm being weighted to a degree suf-
and disposed concentric to the center of the ficient to counterbalance the force applied diaphragm and constituting a fulcrum to the center of the diaphragm to vibrate it.
5 whereby the perimeter of the diaphragm In testimony whereof I hereunto affix may flex as the diaphragm vibrates and, my signature.
means located adjacent the center of the dia-
phragm whereby force may be applied

DAVID A. SEALEY.
